UNITED STATES PATENT OFFICE.

EDWARD A. CLARK, OF SALINE, MICHIGAN, ASSIGNOR OF ONE-HALF TO JULIUS HERTLER, OF SALINE, MICHIGAN.

PARLOR FOOTBALL GAME.

Application filed June 15, 1923. Serial No. 645,627.

To all whom it may concern:

Be it known that I, EDWARD A. CLARK, a citizen of the United States of America, residing in the village of Saline, county of Washtenaw, State of Michigan, have invented certain new and useful Improvements in a Parlor Football Game, and declare the following to be a full, clear, and exact description of the same, such as will 10 enable others skilled in the art to which it pertains to make and use the same, reference being had to the accompanying drawings, which form a part of these specifications.

The object of my invention is to provide 15 a game that can be played indoors, and by the use of a playing board and men, in a similar manner to the games of chess or checkers now so commonly known, but played and regulated by rules imitating and 20 duplicating the plays and moves in the field foot ball game well known in athletics.

A further object is to provide a playing 25 board so constructed that it is adaptable to movements of men placed thereon, to imitate the plays and movements of the ordinary foot ball game, by the use of substitute rules and regulations.

A still further object of my invention is to 30 invent a parlor game that is adaptable to scientific rules, and is intellectual and instructive, and can be manufactured at a low cost.

These several objects are secured in their 35 preferred form by the construction and arrangement of the playing board and the substitute rules governing the game.

Similar parts on the drawings are marked by similar numerals.

Fig. 1, is a plan view of the playing board.

40 Fig. 2, is a side view of the dice ball.

Fig. 3, is an end view of the dice ball showing the central section thereof for the face numbers.

45 Fig. 4, is a plan view of one of the playing men.

Fig. 5, is an edge view of one of the playing men.

50 Fig. 6, is an edge view of the playing board, showing the means for folding the board when not in use.

I will now describe more fully the detailed construction of the playing board and the component parts thereto with the rules required for playing the game.

55 The game consists of the playing board as

shown in the Fig. 1, representing the field, and twenty two men as shown in Fig. 4, together with the dice-ball as shown in the Fig. 2. The game requires two players, one being stationed at each end of the board, and each having and controlling eleven playing men. All movements of the game are controlled by the dice-ball, while the rules governing the game are similar to those used in the game of field foot ball, although 60 slightly modified to make them adaptable to the playing board. The men —1— are made of circular discs shown in Fig. 4, although various sizes shapes and designs may be used if desired, and are used to indicate 65 the position of the foot ball players on the field. The dice-ball —2— is shaped similar to a foot ball, but having a central portion cut in a hexagonal shape, forming faces thereon to retard the rolling of the ball and 70 to retain same in a stable position on the playing board. Each face of the ball bears a number, ranging from —1— to —6— inclusive, but not in a consecutive order, and no two adjacent faces thereon bearing consecutive numbers. Both the playing men 75 and the ball may be made of wood, or any suitable material, and polished or finished as desired. The game can be played equally 80 with the ordinary dice. The playing board —3— is made of thin material, preferably of card board, and of a size suitable for holding in the laps of two players. The board being formed of two sections, and hinged together at the center along the line —AA—, by means of the cloth hinge 85 —B— glued to the upper surfaces of the adjoining edges, for the purpose of folding the board when not in use, and protecting the field design. The upper surface of the 90 board represents the playing field for the game, having the goal posts —C— at each end of the field. The field between the goal posts is divided into twenty sections by the transverse lines —E—, indicating yard lines, 95 and so designated by the figures along the edge of the board, representing the number of yards the line is from the goal line. Each section line indicating a five yard advance. The field is also divided into eleven 100 longitudinal strips extending the entire length of the playing board, as indicated by the parallel lines —G—. The intersection 105 of the transverse lines —E— and the longitudinal lines —G—, divide the field into 110

small sections, each of which carries a number ranging between one (1) and six (6) inclusive, so arranged that no two adjacent spaces are occupied by consecutive numbers, 5 in any direction, either in parallel, transverse or diagonal directions. It is desirable that all of the numbers appear in all yard lines.

No particular arrangement is required, 10 but most desirable to keep the numbers so arranged as to provide the greatest combination possible, in order to utilize the plays secured by rolling the dice-ball. Two extra yard lines are provided back of the 15 goal posts —C— to provide space for the extra men back of the front line men, when the goal play is made. The playing board is symmetrical about the center line —AA—, so arranged that both sides carry the same 20 arrangement and position of all numbers thereon.

In playing my game of parlor foot ball, each player takes a position at opposite ends of the playing board, back of the goal posts, 25 and having eleven men at his command of different color than his opponent. The playing men are lined up on each side of the center line of the board, marked —AA—, each having seven men in the front row, as 30 positioned in the fifty yard line directly opposite those of his opponent. The remaining four men may be arranged on the board as desired, but must have some men in each of the forty five, and forty yard 35 lines. In other words, the player must always occupy three successive yard lines in the formation. The position as indicated on the board in Fig. 1, represents one arrangement that may be made. The players 40 are then ready to start the game. Each player rolls the disc-ball once, and the player receiving the highest number as indicated by the top figure on the dice-ball, takes possession thereof, and starts the game, being 45 confined to the following rules. He may use either the end run or line buck, or forward pass, or may punt, choosing his move as the game develops. The player may roll the dice-ball three times for an end run or 50 line buck, twice for a forward pass, and only once for a punt, and in all cases counting the number on the top face of the ball. In the end run or line buck, the player has three downs, or trials, in which to make the 55 ten yard gain, while in the forward pass, or punt, he has only one. If he chooses to move by the end run or line buck, he then rolls the dice-ball three times, and if the three numbers secured, correspond to a like 60 combination of adjacent numbers on his opponent's field, unoccupied by his opponent's men, each number being located in different yard lines occupied by the opponent's men, the player gains five yards and one down. 65 The player has three downs, or trials, to

make a ten yard advance, and may repeat the play if desired. If he fails to gain the ten yards in three downs, or trials, he then forfeits the ball to his opponent. The adjacent numbers on the opponent's field may 70 be taken from the square directly in front of the preceding number chosen, or at a diagonal direction, but the combination must comprise numbers lying in each of the three yard lines, and in squares unoccupied by his opponent's men, and reading in the order obtained from the ball, the first number being in the front line occupied by his opponent. Thus, combinations as indicated by the dotted lines —H— on Fig. 1, are required in order to entitle the player to advance on the field, being as follows; 541— 546— 513— 516— 515— 543— 545— 216— 213— 243— or 245, while another series of 80 combinations may be secured on the opposite side of the board. The opponent may spread the back four men in any position desired to block the play. If the player succeeds in gaining ten yards in three downs, or trials, he continues his play. Should the prospects be doubtful as to making the ten yard gain in the three trials, he may abandon the end run or line buck move, and adopt one of the other plays named, in which case he must call the word, "Shift," and 90 allow his opponent to rearrange his men on the field to meet the play, and may remove two of the men from the front line to aid in the new formation, leaving at least five men in the front line, and distributing the rest as desired over the two succeeding yard lines. If the player chooses the forward pass, he rolls the dice-ball twice, and if he secured numbers in the opponents second and third yard lines, not occupied by the 100 opponent's men, he advances his men fifteen yards, but if the number in the dice-ball in either throw, is covered by any of the opponent's men in the second and third lines, it is an intercepted pass and the player 105 loses the ball. If the player should try the punt, he rolls the ball but once, and the number indicated thereby must correspond to some number on the third line of his opponent, not occupied by the opponent's men, and if successful he advances his men ten yards. In either the forward pass or the punt, the player loses the ball to the opponent. The game continues until one of the players succeed in placing his front line men over his opponent's goal, which constitutes a touchdown and counts six points for the player. If the player tries a punt, and secures a number on the dice-ball lying between the goal stakes —K—, he gains an 115 extra point. The players may settle upon the period of time to constitute a game, and the one having the highest score is 120 winner.

Various plays may be added to substitute 130

for the numerous moves on the foot ball field, the main object being to follow the foot ball rules as nearly as possible in adapting the game to the playing board.

5 I do not wish to be confined to the exact construction and arrangement of my playing board, or the exact number of spaces or numbers thereon, but claim any and all forms of parlor foot ball games that is substantially similar to the one herein set forth.

Having fully described my parlor foot ball game, what I claim as my invention and desire to secure by Letters Patent is:

15 1. A parlor foot ball game of the character described comprising a playing board, horizontal and transverse lines thereon for dividing the field into sections similar to the foot ball field having a figure in each section, imitation playing men for recording the movements thereon, a dice-ball for determining the plays to be recorded.

20 2. A parlor foot ball game of the character described comprising a playing board, goal posts positioned at each end of said board, transverse yard lines ruled across said board to designate position on the field, rows of numbers extending the full length

of each yard line, and so arranged as to form longitudinal alignment of said figures on the board, playing men for recording the movements made on said board, a dice-ball with number on each face thereof corresponding to the numbers on the board.

3. A parlor foot ball game substantially as set forth comprising a playing board having goal posts positioned at each end thereof, transverse yard lines ruled across said board to designate position on the field, parallel longitudinal lines extending lengthwise of the playing board, dividing said board into small sections, a number placed in each section, said numbers ranging from (1) to (6), inclusively, numbers along the edge of the board to indicate the distance of the yard lines from the goal, imitation playing men for recording position of the plays on the various numbers on the board, a dice-ball having faces thereon, said faces numbered from (1) to (6) inclusively, but not consecutively.

45 In witness whereof, I sign these specifications.

50 EDWARD A. CLARK.
